DESIGN FOR A TASSEL

Charles N. Merralls, Los Angeles, Calif.

Application March 18, 1938, Serial No. 75,912

Term of patent 14 years

To all whom it may concern:

Be it known that I, Charles N. Merralls, a citizen of the United States, residing at Los Angeles, in the county of Los Angeles and State of California, have invented a new, original, and ornamental Design for a Tassel, of which the following is a specification, reference being had to the accompanying drawing, forming a part thereof.

Fig. 1 is an elevation of the tassel of my invention;

Fig. 2 is a plan view of the upper end of the tassel shown in Fig. 1; and

Fig. 3 is a plan view of the lower end of the device embodying my invention.

I claim:

The ornamental design for a tassel, as shown.

CHARLES N. MERRALLS.
